RADIATOR FIN STRUCTURE

Willard O. Emmons, Lockport, N. Y., assignor to
General Motors Corporation, Detroit, Mich., a
corporation of Delaware

Application May 22, 1936, Serial No. 81,173

4 Claims. (Cl. 257—130)

This invention relates to a detail structural change in a radiator core of the type shown in Emmons and Ramsaur Patent No. 1,998,663. It has to do with the formation of the fins for the effective transfer of heat from the fin surface to the particles of air which move through the core.

It is well recognized that air is a poor conductor of heat and that transfer from one particle to another in an air stream is slow. Therefore, with a fast moving air stream only those particles which wipe the radiating surface become heated. As the temperature of a wiping particle rises, its rate of heat absorption slows down and the area of surface which a given particle can wipe without becoming practically ineffective is limited. For the most efficient working of an air stream it is important that the maximum number of particles in the air available be brought into fin wiping contact. The depth of a core and the spacing of water tube fins are chosen with these things in mind and additional attempts are made to disturb the air stream flow for a rearrangement of the air particles in the moving stream usually through the use of baffles or other devices which impart to the stream a tortuous path and in some measure cause a greater number of air particles to wipe the radiating surface than occurs with uninterrupted air cells having straight and smooth walls. Such baffles necessarily obstruct and restrict free flow and reduce the amount of air which a core can pass under given conditions.

It is an object of the present invention to provide an improved fin structure which not only works a maximum number of air particles but does so without appreciable obstruction to free flow. A further feature of importance is that there is involved only a slight modification of the existing structure and aside from the fact that no expensive and complicated manufacturing changes are required for its production, it is simpler in design and easier and cheaper to form.

In the preferred embodiment there is involved a serpentine separator strip to be located in the space between adjacent tubes so that angularly related fins extend almost straight across from one tube to the other for rigidity in assembly and each has a number of transverse slits therein which divide the fin into a succession of separate sections each of which lies in a plane parallel with the direction of air flow but out of line with the neighboring fin sections. Thus the successive sections of the fin are at various heights in the air stream wherefore each cuts into a different stratum or in other words a fresh portion of the

air stream, and since the sections are all of short length and parallel to the direction of flow the individual air particles do not become saturated before leaving the surface and move on substantially straight lines throughout the depth of the core, sweeping smoothly over the fin surface with which they contact. Consequently, resistance to flow is small and the core not only passes a large amount of air but obtains work from a great percentage of the particles in the stream.

For a better explanation of the invention reference will be made to the accompanying drawing wherein Figure 1 shows a radiator assembly for use with an automobile engine cooling system; Figure 2 shows on a much larger scale a fragment of the core assembly; Figure 3 is a detail view looking at the side of the separator plate without the water flow tube attached thereto; Figure 4 is a section taken on line 4—4 of Figure 2, and Figure 5 is a detail perspective view of portions of two of the fins.

Referring to the drawing Figure 1 shows inlet and outlet headers 1 and 2 at the top and bottom of a core assembly 3. As will be understood the core comprises a number of spaced tubes connecting the headers 1 and 2 for the flow in thin streams of cooling liquid, the heat from which is transferred to the metal of the tubes and the fins associated therewith, for absorption in the air which is passed between the tubes. These spaced water flow tubes may comprise a pair of mating plates 4 and 5 formed as disclosed in the aforementioned Emmons and Ramsaur Patent No. 1,998,663 with their opposite edge portions corrugated so that the plates are fitted together in spaced relation and sealed along both sides. Immediately adjacent the internested edges each plate is provided with a row of rounded embossments 6 which serve to center and locate the seating portions of the separator or fin strip. The serpentine separator strip provides a series of angularly related fins joined in succession by the reversed bends 7 along opposite sides and which alternately engage the walls of adjacent water tubes along lines between adjoining bosses 8. To hold the parts in assembled relation and afford a good thermal bond the seating portions of the separator strip and wall plates may be soldered or otherwise joined. Each fin, therefore, is common to the water tubes on opposite sides thereof for the dissipation of heat from both tubes.

In the present case each fin is provided at longitudinally spaced intervals with transverse slits which extend across the fin between the apexes

formed along each side in cooperation with the angularly related fins above and below the same. The fin is, therefore, divided into a longitudinal succession of separate sections all integral with both bends along opposite sides. These sections are numbered 8, 9, 10, 11, 12 and 13 in Figure 4.

With reference to the end section 8 the sections 9 and 11 are pressed above and lie in planes out of alinement with each other and the end section 10 8, while the alternate sections 10 and 12 are pressed below and also lie in planes out of alinement with each other and the section 8. As can be seen in the drawing, the several sections are straight from end to end and their respective 15 planes are all at right angles to the front face of the core or parallel to the direction of air flow, wherefore the air particles sweep through the core without substantial deflection from a straight line uninterrupted course. However, since the 20 cooperating sections in adjacent fins extend into a given air cell at various heights the leading edges of the succeeding fin sections cut into new strata as the air column progresses through the cell and, therefore, any given air particle will 25 wipe but one fin section of the group.

The period of wiping contact will be predetermined by proper selection of fin section length so that the temperature rise of the entire column after the group of fin sections has been traversed 30 will be relatively small and the ability of the column to absorb further heat will still be present to a large degree. Consequently, one or more additional groups of similarly formed fin sections may be provided in tandem relation in the same 35 fin strip. Such groups are indicated in Figure 3 at A, B and C. The extent to which such repetition may occur is limited to an eventual temperature rise to the point where rapid transfer no longer obtains but in any event enables the 40 depth of the core to be slightly increased. Where more than one group of fin sections are formed the endmost sections as at 8 and the intermediate sections 13 all lie in the same plane and similarly the corresponding fin sections of the several 45 groups extended in common planes and, theoretically, the fin sections in a given plane will be wiped by the same air particles. However, inasmuch as the coplanar fin sections are spaced a substantial distance apart there will be a sufficient interval for some inter-particle heat transfer which along with such diffusion as takes place 50 results in the presentation of a surface layer to a successive fin section slightly lower in temperature than that which has left the preceding coplanar fin section.

From the above it will be evident that a great number of air particles will sweep the radiating surface each for a short period in its passage through the core without encountering resistance 55 substantially greater than would be the case if the cell walls were continuous between front and rear faces of the core.

I claim:

1. In a radiator, a set of water tubes connecting the upper and lower tanks; an intermediate indirect cooling strip of zigzag formation, between each of said water tubes, the portions of said intermediate strip between the apexes thereof having one or more sections on a plane with the ends of said portions; and having between said ends and said sections and between said sections, a succession of transverse plates punched and transversely severed from the strip portion of a width substantially equal to that of said sections, each of said plates being on a plane different from that of next adjacent plates and of said sections and of said ends, and each of said plates of one set being on a plane with a similar plate of another set.

2. In a radiator core having spaced tubes, a separator strip between each tube and the next adjacent tube, each separator strip being of zigzag formation with succeeding runs spaced longitudinally of the tubes and the apices between adjacent runs seated on the tubes in alternate relation, the material in each apex being continuous across the width of the strip 2 on a straight line, said runs being common to both tubes and each having a series of spaced transverse slits extending thereacross from adjacent the apex on one side to adjacent that on the other side to provide in each run a bank of 30 fins joined together only at the apices at both sides, with the endmost fins of the bank in a common plane and some of the intermediate fins pressed above and others below said plane, and all of said intermediate fins of the bank being 35 in planes offset from one another and the endmost fins, all said fins being in substantially rectangular relation to the face of the core.

3. In a radiator core, a tube separator comprising a single strip of metal providing heat 40 radiating surface common to a pair of adjacent tubes, and having a series of spaced transverse slits to provide a succession of individual fins joined together along opposite sides and extending on lines normal to the face of the core, said 45 fins being arranged in groups, with the endmost fins of each group in a common plane and the intermediate fins in planes offset to one another and alternately above and below the common plane of the endmost fins.

4. A tube separator of the character described 50 having a bank of fins successively severed by transverse slits and joined together along both sides, the endmost fins of the bank being coplanar and all of the several intermediate fins 55 being out of coplanar relation with said endmost fins and with each other, certain of said intermediate fins lying above and others below the plane of the endmost coplanar fins, and all the fins lying in planes substantially coincident with 60 the normal direction of air flow.
